The ornamental design for a mister water cap, as shown and described.

DESCRIPTION

FIG. 1 is a top view of a mister water cap.

FIG. 2 is a front view thereof.

FIG. 3 is a bottom view thereof.

FIG. 4 is a right side view thereof.

FIG. 5 is a left side view thereof; and,

FIG. 6 is a top perspective view thereof.

The broken lines in the drawings represent unclaimed environmental subject matter and form no part of the claim.

The straw portion of the mister water cap has the length shown in FIG. 6. The straw is shown with break lines in FIGS. 2, 4 and 5 to fit the assembly onto the drawing sheet.
